UNITED STATES PATENT OFFICE.

EDMUND F. DUNN, OF YONKERS, NEW YORK, ASSIGNOR TO ALEXANDER SMITH & SONS CARPET COMPANY, OF YONKERS, NEW YORK, A CORPORATION OF NEW YORK.

LOOM.

Application filed May 29, 1922. Serial No. 564,337.

To all whom it may concern:

Be it known that I, EDMUND F. DUNN, a citizen of the United States, residing at Yonkers, county of Westchester, and State 5 of New York, have invented certain new and useful Improvements in Looms, fully described and represented in the following specification and the accompanying drawings, forming a part of the same.

10 This invention relates to improvements in looms.

It is the object of the present invention to provide an improved pawl shifting mechanism for power looms of that class in 15 which the tuft spools are carried by a pair of chains or equivalent carrier, and in which the chains are arranged to be given a step-by-step movement to bring successive tuft spools into position for use, whereby the operator, when on one side of the loom, may 20 control pawls on the opposite side thereof to reverse the chain shaft and bring one or more tuft spools into operative position a second or more times in case of a defect in 25 weaving, or may start and stop the chains without reversing, as desired.

For a full understanding of the invention, a detailed description of the same will now be given in connection with the accompanying drawings and the novel features 30 thereof then be pointed out in the claims.

While the accompanying drawings show only those portions of a loom necessary for an understanding of the present invention, 35 a full showing of one type of loom designed for weaving Axminster or moquette carpets, and to which the device is especially applicable, is disclosed in United States Letters Patent No. 233,290, dated October 40 12, 1880, and No. 529,636, dated November 20, 1894, in which the tuft spools are successively removed from the chain carriers for insertion of a row of tufts therefrom and then returned to the carriers after such 45 row has been inserted, although the device obviously may be applied to other types of looms for weaving tufted fabrics. As the construction and operation of such looms are well understood, the present improvement 50 will be described only so far as necessary in connection with the accompanying drawings, in which—

Figure 1 is a vertical section of a portion of a loom including the chain shaft with 55 the present device applied thereto;

Figure 2 is an end view looking to the right in Fig. 1;

Figure 3 is a detail of the pawl operating handle and segment for holding the same in adjusted position;

Figure 4 is a section on the line 4—4 of Fig. 1, and

Figure 5 is a view similar to Fig. 4, but showing the chain shaft pawls in neutral or inoperative positions.

Referring now to the drawings, and particularly to Fig. 1, the shaft A carries sprockets B over which pass chains C, which are given a step by step motion by ratchet mechanism hereinafter described to properly position the tuft spools D for use, such spools being removably mounted in carriages E secured to the chains C in a well-known manner. The ratchet mechanism for imparting movement to the chains C, 75 and by which the chains may be given either a forward or backward movement, or stopped, consists in the present case of ratchets 10, 11 mounted on one end of the chain shaft A, the teeth of each ratchet 80 wheel being oppositely disposed to those of the other wheel, so that when one or the other of the pawls 1, 2 are adjusted as hereinafter explained to engage either the ratchet 10 or 11 respectively, the chain shaft 85 A will be given a forward or backward step by step motion through cam lever 12 and link 13 connected to rocking lever 3 mounted on the shaft A. To each end of the rocking lever 3 is connected a lever 4 connected to arms 5 rigidly secured to pinions 6 in mesh with each other and mounted on a member G secured to the loom frame, so that as either the pawl 1 or 2 is set to engage its ratchet 10 or 11, or when both pawls 95 are so positioned as to be out of engagement with their ratchets, the motion imparted to the rocking lever 3 will continue, and, dependent on the position of the slide frame 20, either advance, reverse or permit the 100 chain shaft A to remain stationary. The means for bringing either pawl 1 or 2 into engagement with its ratchet 10 or 11, and for keeping both of the pawls out of operative engagement with said ratchets, comprise standards 14, 15 secured to the loom frame at opposite sides thereof, in which are journaled the ends of a shaft 17 arranged 105 parallel to but vertically over chain shaft A. A pinion 18 secured to one end of shaft 110

17 is arranged to engage a gear rack 19 formed on or secured to the top of a slide frame 20, such slide frame having depending arms 21, 22, preferably of arcuate form 5 near their extremities and in which are formed arcuate slots 23 in which ride bowls 24 formed on the ends of the pawls 1, 2, the latter being pivoted to the rocking lever 3 in any well known manner. On the opposite end of shaft 17 is a lever 25 which, in the operation of the device, is arranged to be set in any one of three positions by engagement with notches *a*, *b*, *c* in a segmental plate 26, whereby when the handle 10 is turned shaft 17 will be revolved slightly and, through pinion 18 and rack 19, move slide frame 20 transversely. As the bowls 24 of pawls 1, 2 ride up or down in slots 23, each pawl is swung on its pivot and their 15 ratchet engaging ends either brought into position for engagement with or disengagement from the ratchet with which it is intended to cooperate to either turn chain shaft A forward or backward. When the rack 20 positions the slide frame 20 so as to keep both pawls out of engagement with the ratchets, movement of the chain shaft A of course ceases. For permitting ready adjustment of lever 25 in the notches in segmental plate 26, and to securely hold such 25 lever in adjusted position, shaft 17 is so mounted in its bearings in standards 14, 15 as to have a slight longitudinal movement, and a coil spring 27 mounted on such shaft 30 between central bearing bracket 28 and adjustable collar 29 constantly forces such shaft and therefore lever 25 to the right in Fig. 1 and against segmental plate 26.

The operation of the device will be clear 40 from the foregoing and the following brief statement: When handle or lever 25 is set in notch *a* the parts will be in the positions shown in Fig. 4 and the chain shaft A will, through engagement of pawl 1 with ratchet 45 10, impart a forward step-by-step motion to such shaft by the mechanism above described for rocking the lever 3 to which the pawls are pivoted, as above stated. When the lever is in notch *b*, the parts will be in 50 the positions shown in Fig. 5 and the pawl bowls 24 will be so positioned in the slots 23 as to throw the ratchet-engaging ends of the pawls 1, 2 out of engagement with their ratchets, so that while the rocking lever 3 55 continues to oscillate, movement of the chain shaft will cease. When the lever is set in notch *c*, the slide frame will be in a position opposite to that shown in Fig. 4 and pawl 2 will, therefore, be thrown into engagement with its ratchet 11 while pawl 1 60 will be held out of engagement with its ratchet and the chain shaft will be given a step-by-step movement in a direction reverse to that in which it was turning when 65 the lever was in notch *a*, the lever being

shifted to notch *c*, of course, when it is desired to bring any one of the tuft spools back to proper position for re-use to correct a defect in the weave, or for other reasons.

70 While the invention has been shown and described in what is now believed to be its best form, it will be obvious that various changes and modifications may be made therein to adapt it to looms of other types, 75 while still retaining the invention defined by the claims.

What is claimed is:

1. The combination with a loom for weaving tufted fabrics in which the tuft spool carriers are moved by an intermittently operated member, of a plurality of oppositely toothed ratchets mounted on said carrier-moving member, a rocking lever having pawls pivoted thereto arranged to engage said ratchets, a slide frame having means for swinging said pawls on their pivots to throw their ratchet-engaging ends into and out of engagement with said ratchets, and means for moving said slide frame 80 from the side of the loom.

2. The combination with a loom for weaving tufted fabrics in which the tuft spool carriers are moved by an intermittently rotated shaft, of a plurality of oppositely toothed ratchets mounted on said shaft, a rocking lever having a plurality of pawls pivoted thereto, a slide frame arranged to cooperate with said pawls to throw the same into and out of engagement with said ratchets, a rack and pinion for moving said slide frame, and means at the opposite side of the loom frame for turning said pinion to move said rack and thereby control the movement 95 of the chain shaft.

100 3. The combination with a loom for weaving tufted fabrics in which the tuft spool carriers are moved by an intermittently rotated shaft, of a plurality of oppositely toothed ratchets mounted on said shaft, a 110 rocking lever having a plurality of pawls pivoted thereto, a slide frame having depending arms, arcuate slots formed in said arms, bowls formed on the pawls arranged to ride in said slots for swinging said pawls 115 on their pivots to bring their ratchet-engaging ends into and out of operative engagement with said ratchets, and means operable from the opposite side of the loom for controlling the movement of said slide frame.

120 4. The combination with a loom, of intermittently rotated shaft A, oppositely toothed ratchets 10, 11 for actuating said shaft, a rack, pawls 1, 2 for operating said ratchets, slide frame 20 for throwing said pawls into and out of position to engage said ratchets, 125 shaft 17 carrying pinion 18 for engagement with rack 19, and handle 25 for turning said shaft to thereby control the movement of the slide frame.

5. The combination with a loom, of intermittently rotated shaft A, oppositely toothed ratchets 10, 11 for actuating said shaft, a rack, pawls 1, 2 for operating said ratchets, 5 slide frame 20 for throwing said pawls into and out of position to engage said ratchets, shaft 17 carrying pinion 18 for engagement with rack 19, handle 25 for turning said shaft to control movement of said slide frame, segmental plate 26, and spring 27 co-¹⁰ operating with bracket 28 and collar 29 to hold said handle in frictional engagement with said plate.

In testimony whereof, I have hereunto set my hand,

EDMUND F. DUNN.
